COMBINED MANICURE SET AND CASE

Alfred Edouard Lamarthe, Paris, France

Application June 14, 1954, Serial No. 30,973

Claims priority, application France February 3, 1954

Term of patent 14 years

(Cl. D86—10)

FIG. 1.

FIG. 3.

FIG. 2.

FIG. 4.

FIG. 5.

Figure 1 is a plan view of the combined manicure set and case, showing my new design in closed position;

Fig. 2 is a plan view of the combined manicure set and case, shown in Fig. 1, in open position;

Fig. 3 is an end view of the combined manicure set and case shown in Fig. 2;

Fig. 4 is a bottom plan view of the combined manicure set and case in open position; and

Fig. 5 is an elevational view of the combined manicure set and case shown in Fig. 2.

The broken lines appearing in the drawing are for illustrative purposes only.

I claim:

An ornamental design for a combined manicure set and case, as shown and described.
